(57) **CLAIM**

The ornamental design for a G4 side pin light-emitting diode adjustable plug angle housing assembly, as shown and described.

DESCRIPTION

FIG. 1 is a top front perspective view showing the G4 side pin light-emitting diode adjustable plug angle housing assembly; FIG. 2 is a top rear perspective view showing the G4 side pin light-emitting diode adjustable plug angle housing assembly; FIG. 3 is a bottom perspective view showing the G4 side pin light-emitting diode adjustable plug angle housing assembly adjusted in the 10° down plug detent slot position; FIG. 4 is a bottom perspective view showing the G4 side pin light-emitting diode adjustable plug angle housing assembly adjusted in the 0° down plug detent slot position; FIG. 5 is a side elevational view showing the G4 side pin light-emitting diode adjustable plug angle housing assembly adjusted in the 10° down plug detent slot position; FIG. 6 is a side elevational view showing the two parts of the G4 side pin light-emitting diode adjustable plug angle housing assembly adjusted in the 10° down plug detent slot position; FIG. 7 is a side elevational view showing the G4 side pin light-emitting diode adjustable plug angle housing assembly adjusted in the 0° down plug detent slot position; FIG. 8 is a side elevational view showing the two parts of the G4 side pin light-emitting diode adjustable plug angle housing assembly adjusted in the 0° down plug detent slot position; FIG. 9 is a back view showing G4 side pin light-emitting diode adjustable plug angle housing assembly adjusted in the 10° down plug detent slot position; FIG. 10 is a back view showing the two parts of the G4 side pin light-emitting diode adjustable plug angle housing assembly adjusted in the 10° down plug detent slot position; FIG. 11 is a back elevational view showing the G4 side pin light-emitting diode adjustable plug angle housing assembly adjusted in the 0° down plug detent slot position; FIG. 12 is a back elevational view showing the two parts of the G4 side pin light-emitting diode adjustable plug angle housing assembly adjusted in the 0° down plug detent slot position; FIG. 13 is a front elevational view showing the G4 side pin light-emitting diode adjustable plug angle housing assembly adjusted in the 10° down plug detent slot position;

FIG. 14 is a front elevational view showing the G4 side pin light-emitting diode adjustable plug angle housing assembly adjusted in the 0° down plug detent slot position;

FIG. 15 is a top plan view of the G4 side pin light-emitting diode adjustable plug angle housing assembly;

FIG. 16 is a top plan view showing the two parts of the G4 side pin light-emitting diode adjustable plug angle housing assembly;

FIG. 17 is a top plan view of the G4 side pin light-emitting diode adjustable plug angle housing assembly showing where the section cut is to be made; and,

FIG. 18 is a Section "I-I" view of the G4 side pin light-emitting diode adjustable plug angle housing assembly. The broken lines, showing the remainder of the G4 side pin light-emitting diode adjustable plug angle housing assembly, are for illustrative purposes only, and form no part of the claimed design.
